CABLEWAY.

Application filed August 11, 1926. Serial No 128,681.

This invention relates to cableways or ropeways for transporting and lowering or raising material as, for example, depositing material in large masonry or concrete dams.

5 It includes not only the cableway itself but also the necessary plant and working apparatus therefor and covers also the method of or manner of working which is involved.

The hourly capacities of cableways in spite 10 of high traversing speeds and heavy individual loads are comparatively low if called upon to deposit material over or raise material from a long length. This is due mainly to the following reasons:

15 (1) The cableway is standing idle whilst the empty bucket is being detached from and the full bucket being attached to the carrier or whilst the bucket is being loaded from a hopper;

20 (2) Time is wasted in traversing the empty bucket back to the loading point; and

(3) On a long cableway, say 2000 feet long, a very appreciable amount of time is occupied in traversing the loaded bucket.

25 The object of this invention is to provide a continuous cableway adapted to have a number of loaded buckets on one cable moving forward from the loading point to the unloading point and all empty buckets re-

30 turning on preferably a separate rail or stationary cable. In the preferred embodiment, the buckets will pass round a closed circuit normally travelling in one direction along any particular section of the circuit.

35 The objects are mainly:—

(a) To save all time wasted on existing cableways referred to in the preceding paragraphs;

40 (b) To obtain a cableway with an hourly capacity far greater than has heretofore been accomplished over a long span;

(c) To save the wastage of power absorbed in raising empty buckets;

45 (d) To obtain a cableway which is capable of traversing hoisting and lowering loads over a distance, say five or more times greater than is practicable with any type of cableway constructed heretofore; and

50 (e) To, in the preferred embodiment, convert the usual type of bi-cable ropeway into a cableway by making the hoisting or traversing rope also raise and lower loads and still enable the buckets and carriers to auto-

matically leave both the rail or stationary cable at the end shunts and also disengage 55 from the traversing rope at the loading point and also at the return terminal station if desired.

The invention comprises a method or manner of working a cableway for transporting 60 material from one or more fixed loading points and depositing the same anywhere along the cableway's working length, which consists in utilizing a standing rope or rail for the support of the bucket carriages, a 65 traversing rope adapted to move said carriages, and a lowering and lifting rope to control the vertical elevation of the buckets, said lowering and lifting rope passing through or engaging said carriages in such a manner 70 that the said buckets or loads are or may be supported by a loop in the said rope in their carriages, with provision whereby sufficient slack may be given in said lowering and lifting rope to allow of at least one bucket or load 75 being lowered in its loop in the said rope to a desired distance below its carriage, suitable braking or controlling gear being provided so that the lowering operation may be controlled and the excess weight of a desired loaded bucket may be utilized to lower it and at the same time to raise a previously lowered and emptied bucket back to its carriage, the slack in the lowering and lifting rope being utilized for this said purpose. 80

85 In this method or manner of working according to the preferred embodiment, a single rope is used for both traversing purposes and for lowering and lifting purposes, said rope being adapted to form a lowering loop from 90 any desired bucket carriage and to traverse the said carriage, with or without a lowering loop of slack rope therein, when the said carriage is suitably clamped thereto.

95 The weight of the bucket or load may be supported directly from the carriage and thus be directly carried by the standing rope or rail, but provision is made whereby the said weight may, when desired, be transferred so as to be carried by the bight of, or loop in, the lowering and lifting rope, or vice versa, the arrangement being such that when carried on said lowering and lifting rope the bucket may, under desired conditions, be lowered from or raised to its carriage for working 100 purposes. 105

According to this invention, when the bucket or load is supported directly from the carriage, and thus from the standing rope or rail, it may be so arranged that it can be lifted, moved clear of, or completely disengaged from the traversing rope and/or the lowering and lifting rope.

The standing rope or rail used with the above described arrangements may be made 10 into a closed circuit by shunt rails or the like at main loading or reversing points so that the carriages and buckets may follow each other in sequence around the circuit.

The invention includes in fact a method or 15 manner of working a cableway wherein when the working is started a procedure is adopted substantially as hereinafter described and as will clearly be set out in connection with the drawings for lowering and unloading the first 20 bucket, including the paying out of slack in the lowering and lifting rope which is needed for the purpose.

It also includes a method or manner of 25 working wherein, when normal working conditions are established, and the buckets are being lowered and unloaded in sequence, the emptied buckets are raised again using for that purpose the potential energy possessed by full buckets which are to be lowered and 30 unloaded in their turn, the method of manipulation and/or sequence of operations being substantially as will hereinafter be fully described.

In these methods or manners, when normal 35 working conditions are established, the traversing and/or the lowering and lifting rope, or the single rope used for said purposes, are or is operated continuously with or around the cableway or desired portion thereof, the 40 carriages being attached and detached and the buckets lowered, emptied and raised again and reconnected to their carriages whilst said ropes or rope are or is continuously moving substantially as described.

The invention also includes the modification 45 of the normal method or manner wherein, instead of working continuously for depositing the contents of buckets of concrete or other material which may be rapidly tipped, the working is intermittent in that the traversing rope and the lowering and lifting rope 50 is or are started and stopped to enable material to be deposited in more exact position substantially as described hereinafter with respect to the depositing of facing stones.

In any of these methods or manners of 55 working, the weight of the bucket or load may be transferred to, or taken off, the bight in, or loop of, the lowering and lifting rope substantially in the manner which will be explained in detail hereafter.

The invention also comprises a cableway 60 adapted to work on a closed circuit system, for example of the general type of an ordinary bi-cable aerial ropeway, adapted to have

buckets or the like following one another in sequence around a substantially closed circuit, wherein the said buckets are supported in turn upon, or from, a rail or stationary cable (and the shunt rails connecting therewith at the loading or return terminal stations), and wherein the loaded buckets or the like, preferably one at a time, may be lowered for unloading at any point along the working section 70 by operating on the slack in a lowering and lifting rope or ropes provided for that purpose, in which lowering operation the excess weights of the said loaded buckets or the like in lowering operate to hoist empty buckets which have previously been lowered and unloaded (or whose loads have been detached), the arrangement being such that the empty hoisted buckets may nevertheless be detached from the said lowering and lifting rope, and if desired, from the traversing rope also, if such is separately used, at the cableway terminal reversing or loading stations, so that the buckets may follow the shunt rails thereat and be reattached to the said lowering, lifting and/or traversing ropes after passing round 80 the shunt, being reloaded at one or at both terminal stations whilst on the shunt, thus permitting of continuous running and operating of the bucket around the circuit.

It also includes such a cableway but having 85 therein a single moving rope both for traversing and also for lowering and lifting the buckets or the like.

The lowering and lifting rope may be 90 adapted to engage or be engaged by the carriages or the like carrying the buckets or loads, and to form a bight or loop in each 100 said carriage, onto which bight or loop the weight of the bucket or the load may be transferred, and in which loop the bucket or 105 load may be lowered to a desired distance (determined by the amount of slack in the said rope) below the standing cable for unloading purposes, and in which loop the discharged bucket or the like may be raised 110 again to approximately its original level relatively to the standing rope.

The lowering and lifting rope as last described may be adapted also at the same time to act as the traversing rope.

The lowering and lifting rope will have 115 means whereby sufficient slack may be given thereto to enable the buckets or the like to be lowered, preferably in sequence, in loops formed by the said slack to a desired level.

The said rope may also be adapted to transmit the necessary power required to raise the cableway empty buckets utilizing the potential energy released when lowering loaded buckets on the cableway and/or also be able 125 in addition to transmit the necessary power to traverse its necessary number of carriages along the cableway.

In any case the cableway may be one having 130 means whereby the load or the weight of

the bucket may be either carried directly by means of the carriage running on the rail or standing cable or, alternatively, may be transferred to be carried by the said carriage through the intermediary of the lowering and lifting rope.

In or for a cableway according to this invention, the carriages may be adapted to run on wheels upon the rail or standing cable and each carriage be arranged to carry a bucket or load suspended therefrom, said carriages having two spaced pulleys each over which the continuous lowering and lifting rope is adapted to pass and between which the said rope is adapted to loop down when the bucket or load is being lowered or raised in said loop, and a bucket or load carrying pulley-wheel resting on the said rope midway between said other pulleys, from which last pulley-wheel the bucket or load may be caused to directly hang when being lowered.

The said carriages will have rope clamping means associated with said spaced pulleys, preferably on the outer sides thereof, whereby the lowering and lifting rope may be clamped as desired at one or at both points to the carriage.

Braking gear will also be provided to control the rotation of one at least of the pair of spaced pulley-wheels and, if desired, rope-gripping gear is also provided to prevent the rope sliding in the pulley-wheel groove.

Blocks and tackle, screw couplings or other equivalent lifting gear may be connected to the carriages proper, and means for working the same, and further means be provided, such for example, as a hook or a pin device, whereby the pulley from which the bucket or load is suspended may be engaged and lifted from, or lowered onto, the bight in, or loop of, the lowering and lifting rope, and whereby, when said pulley is lowered onto said rope, the said pulley may be completely disengaged.

The invention also comprises, as already mentioned, a cableway adapted to be worked in the manner which will be more fully made clear hereafter in detail, comprising a rail or standing cable and the necessary shunt rails therefor to form a closed circuit, a continuous traversing, lowering and hoisting rope or ropes therefor with means for causing said rope to move, and a tensioning device or devices adapted to enable said rope or ropes to be paid out or slackened sufficiently to enable at least one bucket or load on each to be lowered in a loop in said rope the full distance required below the rail or standing cable.

In this cableway, a single rope may be used for the traversing, lowering and lifting functions or, alternatively, a continuous traversing rope and a separate continuous lowering and lifting rope with means for causing each to move may be used, the latter having a tensioning device as last indicated.

For proper working, subsidiary tensioning

means may be provided for placing and sustaining a suitable working tension in the lowering and lifting rope and/or in the traversing rope.

Finally the invention includes a cableway as described in which a single engine, prime mover or motor may be used adapted to cause the lowering and lifting rope to move and, when desired, to take up or pay out the slack in the said rope for the purposes described.

The invention will now be described with reference to the accompanying drawings which it is to be understood are largely diagrammatic.

In these drawings:—

Figures 1 and 2 are a diagrammatic elevation and plan respectively of one end of the cableway showing the driving and tensioning mechanism. In this a single rope is used for traversing and for bucket lowering and hoisting purposes.

Figures 3, 4 and 5 show, also diagrammatically, three positions of a bucket carriage suitable for the said cableway.

Figure 6 is a diagram illustrating a phase in the normal working.

Figure 7 is a diagram illustrating an alternative manner of working where the cableway is used for depositing, say, facing stones for a dam, and

Figure 8 illustrates, also diagrammatically, a cableway in which separate ropes are used for traversing and for lowering and hoisting buckets.

The cableway consists essentially of a rail stationary or standing cable 1 which is connected at the loading or returning stations to a shunt rail 2, and is provided with a bucket lowering and hoisting rope 3, which in the preferred embodiment of the cableway as shown in Figs. 1 and 2, is made continuous and is caused to move and to be used not only for lowering and hoisting buckets but also for traversing the buckets and the carriages or carriers around or along the cable. A separate rope may, however, be used for traversing, if so desired, as illustrated in Fig. 8.

The carriages or carriers will first be described and the method of working the preferred embodiment.

These carriages or carriers are illustrated in Figs. 3, 4 and 5 and it is proposed that each carriage shall be dispatched in normal conditions onto the cableway in charge of an operator, although it may be possible to introduce automatic control, for example by trip operated clockwork or electrical gear, without departing from the scope of the invention.

The carriages 4 run on wheels or a trolley 5 on the rail or standing rope 1.

The normal direction of movement of the carriage is indicated by the arrow on Figs. 3 to 5.

The lower part of the carriage (as shown)

is provided with two clips 6 and 7 by means of which the operator can clamp the traversing rope 3 to the carrier either separately at the front clip 7 or at rear clip 6 or at both clips.

8 is an ordinary pulley for supporting half the weight of the bucket 9 when carried on the traversing, lowering and hoisting rope 3.

10 is a similar rope pulley fitted with a 10 brake drum, such as a band brake which may be operated by means of the hand-wheel 11.

12 is an ordinary rope pulley which carries the full weight of the bucket when suspended on the lowering and lifting rope.

15 Attached to the upper portion of the carrier is a set of rope blocks 13, 14, with tackle 15 rove therein, which are worked by the operator through, say, worm wheel 16 and handle 17. The lower hooks 14 may be attached to 20 the bucket hanger 18 by inserting pin 19.

The method of operating the cableway is as follows:—

When the cableway is working on the construction of a dam, in which for example all 25 material is loaded on the cableway at one end and at a higher level than where the material has to be deposited the operations for running the cableway are as follows. The description is in reference to a preferred form 30 of cableway in which a single rope is used for traversing lowering and lifting.

Loading the cableway at commencement of shift.

35 When the carriages 4 and their buckets 9 are off the rail or stationary cable 1 and supported on the loading station shunt rail 2 the buckets are suspended from the carrier blocks and tackle 13—15 as shown in Fig. 4.

40 Buckets may be loaded from hoppers through shoots or in any manner in which mono-cable or bi-cable ropeway bucket can be loaded.

The sequence of operations may then be as 45 follows:—

Loaded buckets are run from the loading station shunt rail 2 on to the rail cable 1 in a similar manner to those of a bi-cable rope-way.

50 The operator in the bucket carrier 4 then immediately locks the traversing rope 3 to the carrier by means of the front clip 7 (blocks and tackle 13—15 being roved in short).

55 The operator then by means of the worm winch 16—17 and rope blocks 13—15 lowers the bucket hanger 18 until it reaches the position shown in Fig. 5, the loaded bucket hanging with its full weight suspended from or resting on the bight of the rope 3 between pulleys 6 and 7.

The rope 3 is then locked to the carrier by means of clip 6. The rope blocks 13—14 are then further slackened and pin 19 withdrawn.

60 The brake of wheel 10 is then securely ap-

plied and kept on. This brake application is not necessary in the case of the first bucket to be dumped but on all following buckets.

After the first loaded bucket has been despatched a gap is left equal to the normal 70 spacing of the buckets plus twice the depth to which the buckets have to be lowered.

When the first loaded bucket reaches the point at which it has to be dumped, the cableway, that is to say the movement of the traversing rope 3, is stopped.

This is at the commencement of the operation:—

The traversing rope tension trolley 20 and tackle 21 working it (see Fig. 2) is then slackened back the full distance the bucket is to be lowered and the operator in the first loaded bucket unlocks clip 6 and accordingly the weight of the loaded bucket simultaneously takes up the slack as the traversing rope tension trolley 20 supplies it until the bucket reaches the depth desired. The bucket is then dumped and the cableway, that is movement of the traversing rope 3, is then started up again and may run continuously thereafter 90 for the normal working period.

The sequence of operations which may be followed for lowering full buckets and raising empty buckets when the cableway is running normally is as follows:—

Referring to Fig. 6. As soon as the lowered bucket marked Y has tipped, the operator in the next loaded bucket marked X releases the clips 7. He then lowers his bucket by slackening the brake of wheel 10 and in so 100 doing also raises bucket marked Y by taking up its loop in the traversing rope 3, it being noted that the clip 6 on this empty bucket Y is unlocked, enabling the slack to be taken up. The dotted line a, b, c, d, e, f shows the approximate path of the bucket.

In cases where the tension in the traversing rope is insufficient to give the necessary friction in the groove of pulley wheel 10 so that the lowering of the loaded bucket can be 110 properly controlled by the brake, extra pressure may be applied to the rope resting in the groove of pulley 11, for instance through a small pulley or pulleys 22 pressing on the rope.

Immediately the full bucket is dumped, its operator unlocks clip 6 and locks clip 7. Upon the empty bucket having been raised as high as it will go by the lowering of the full bucket, the clip 6 on the empty bucket carriage may 120 be secured again temporarily.

The cycle of the last two operations, that is, lowering a loaded bucket and hoisting the one which has previously been unloaded, may then be repeated throughout the working 125 shift.

To facilitate dumping, the buckets may be fitted with automatic trip gear worked by striking a handle 23 or in other convenient manner enabling them to dump their contents 130

at a desired point on the trigger or handle 23 of the tipping gear being operated.

After a bucket has been raised, the tension in the traversing rope at that point on the line where it has the minimum tension leaves it with a sag as shown in Fig. 3.

The operator may temporarily secure clip 6. He then inserts pin 19 and raises the empty bucket and hanger to a position shown 10 in Fig. 4 by means of the blocks 13—15 and worm winch 16—17. Clip 6 is then unlocked.

When an empty bucket is entering the shunt rail of the return terminal station the operator releases clip 7 and the bucket runs 15 automatically round the shunt rail, if the same is suitably graded.

As soon as the buckets leave the return terminal station shunt rail, the operator again locks clip 7.

When an empty bucket is entering the loading terminal, clip 7 is again unlocked and the bucket runs on to the shunt rail and is ready to be reloaded.

A convenient sequence of operations to follow when closing down the cableway is as follows:—

Empty buckets are sent out without operators but clips 7 thereon are locked, the last bucket lowered and dumped is raised by hauling back the tension trolley 20.

Operation needed when raising loads.

When occasional loads have to be raised at any point along the cableway, this can be 35 done by means of the winch attached to or drum operating the tension trolley 20. When the trolley 20 is slackened back, the empty bucket takes up the slack and falls and may be raised by again hauling in the tension trolley.

The capacity of a cableway is a most important consideration.

The hourly capacity of the cableway according to this invention may be very great. 45 For example, when loaded at one end only and traversing the material say 8000 ft. or more and lowering 200 to 300 ft. and traversing at the comparatively slow speed of 100 yds. per min. when carrying 10 ton net loads 50 the capacity would be approximately 600 tons per hour, or, stated in another way, the hourly capacity of the cableway is equal to 60 times the weight of the net individual loads carried at a spacing of just over 100 55 yds. apart.

The hourly capacity of an ordinary cableway of known type as used today, even if one which is one quarter of the above length and using a traversing speed four times greater 60 is considered, would only be approximately ten times the weight of the individual net loads carried.

If the continuous cableway can be loaded with material at each end, the hourly capacity 65 is then practically double the figures

given above or 120 times the net weight of the individual loads carried.

A convenient form which the driving gear may take is indicated in Figs. 1 and 2.

The continuous cableway can be driven 70 by either an electric motor or by a steam, oil or gas engine, but preferably by motor. The figures diagrammatically show one method which may be adopted in which the motor 24 drives through a flexible coupling 75 25, worm reduction gear 26, and clutch 27 keyed to a horizontal countershaft which by means of bevel gear 28 drives a vertical shaft on which is a pinion 29 gearing into a spur ring bolted to the fleeting or surging 80 pulley 30 round which the hauling or traversing rope 3 is wound. 31 represents a brake.

The diagram also shows how the first loaded bucket of each shift is lowered to the desired depth, the tension trolley 20 being 85 slackened back by paying out rope from drum 34 which may also be driven by the motor or prime mover 24 through the worm reduction gear 26 and clutch 32.

This half of the countershaft is also provided with a brake 33. The rope drum 34 operates on the rope 35 and thus on the system of pulleys 36—37 of the rope falls 21. The set of blocks 36 is fixed and on the rope 35 being hauled in the tension trolley 20 is 90 also hauled in. The rope 3 is carried round the pulley 30 and, as indicated at 3^a, passes round the trolley wheel 20 and thence, as at 3^b, around the pulley 38 and then around suitable guide pulleys 39 to follow the line 100 of the standing cable 1.

The tension weight 40 gives the required initial tension in rope 3 for normal continuous running when loads are carried from the loading station and deposited at a lower level 105 along the dam.

This is due to weight 40 being hung at the further end of the rope 35 so as to place a definite tension in the ropes of the fall 21, the rope from the falls passing over pulley 41 for this purpose.

The tension weight 42 (which is flexibly attached to the underside of tension weight 40) added to the top weight 40 is sufficient to balance the pull on the hauling or traversing rope when the first loaded bucket is being lowered or a load is being hoisted from any point along the cableway.

The rail or stationary cable tension gear would be similar to that of a bi-cable rope-way and would preferably be arranged at the return terminal station. When the continuous cableway is being used for the construction of a dam and transporting concrete or moderate size plums of say 12" to 18" cube, 115 it can be run continuously like a bi-cable rope-way, the essential difference being the provision of the lowering and lifting means which convert the rope-way into cableway.

When the cableway according to this invention 120

tion is being used to transport heavy facing stones or other material requiring greater care in handling and placing, the following working operations are necessary or advisable.

The actual manipulation of the carrier clips 6 and 7, pin 19 and brake 10 will be similar to the method of manipulation when buckets of concrete and plums are being carried, it is therefore, not necessary to describe these operations again in detail. The following description of operations, whilst referring to Fig. 7, clearly explains the method of procedure in regard to depositing facing stones or other material needing greater care in depositing or which need to be placed in more exact position. Assume facing blocks have to be placed at points A and C, the cableway is stopped when the first loaded carrier marked Y is directly over point A. Load Y is then lowered the last few feet until the stone comes to rest on a firm bearing and the slings unhooked. Load X is then lowered at B and its load placed. This operation takes up the traversing and lowering rope loop at Y, thus raising the carrier bottom sheave and slings of Y.

The cableway is then started up and run until carrier marked W is not quite over point A, by which time carrier marked V will be nearly over point B, when the cableway is again stopped. During the period of traversing, load W is lowered and carrier X bottom sheave and sling raised.

In Fig. 7, *g h* shows the approximate path of the load W when being lowered and *h m* the approximate path of the empty slings X when being raised.

The above cycle of operations is then repeated commencing with the final lowering of load marked W alongside load marked Y at point A.

The facing stones could afterwards be picked up and laid in their correct positions by derrick crane.

When it is desired to raise loads at any point along the cableway by use of the hauling or traversing rope, the following procedure may be followed.

The cableway is stopped when an empty bucket is over the point from which it is desired to hoist a load. Rope is paid out from the drum of winch 34 (Fig. 2) which is taken up by tension weight 40 falling until it rests on tension weight 42. Rope is continued to be paid out from the winch drum 34 until the tension in the traversing rope is less than half the weight of the empty bucket and carrier sheave which then takes up the slack and lowers away from the carriage and rail rope.

In Fig. 8 an arrangement of the plant is shown diagrammatically according to which separate ropes are used for traversing and for lowering and hoisting purposes.

According to this diagram, which can of course be modified in many ways, the rail or standing rope 1 is anchored at 1^a and has the usual shunt rail 2 at either end to form a substantially closed circuit. By this term it is meant that the said parts are so arranged that carriages or carriers may be caused to move completely round the circuit of the standing rope and its shunt rails. It does not, however, deny the use of switches and sidings on the said shunt rails if the same are needed so that, if preferred, certain carriers might be taken out of use or by means of which sidings loading operations might be facilitated. The lowering and hoisting rope is indicated on this diagram by 3^c and the separate traversing rope is 43. The carriages or carriers have in this case a separate clip for engaging the said traversing rope 43. This traversing rope 43 passes around suitable guide rollers 47, 47^a. It is taken round the driving wheel 44 and thence round the pulleys 46-45 and back to the standing rope track. 46 is a pulley mounted on a tension trolley and the required tension in the rope 43 may be obtained by operating this trolley in a known manner. The driving wheel 44 is driven in any suitable manner.

Turning now to the lowering and hoisting rope 3^c (Fig. 8), it will be seen that the said rope passes round the guide rollers 48 and 49 and then round the surging wheel 50. It then passes round the guide rollers 48^a 49^a, to again follow the line of the standing cable. The surging pulley 50 is attached to the tackle 51 (only partly indicated) which may be worked by the rope 53 from the rope drum 52. The further end of the rope 53 may pass over a pulley 54 and have suitable tension weights hung therefrom. The arrangement may indeed be somewhat similar to that described with reference to the parts 20, 21, 34, 35, 36, 37, 40, 41 and 42 of Figs. 1 and 2. It will be seen that in this diagram (Fig. 8) no means has been shown for driving the said lowering and lifting rope 3^c. It will, however, easily be realized that driving means can readily be provided, for example the arrangement might be very similar to that described with reference to Figs. 1 and 2, or, if preferred, the pulley 55 at the further shunt station might be the driving pulley.

It is perhaps not absolutely necessary to drive the lowering and lifting rope 3^c because, when this rope is clamped to a carriage and the carriage is hauled round by the traversing rope 43, the said lowering and lifting rope 3^c must also be pulled round. At present, however, it appears that, if the separate ropes 3^c and 43 are used, it would be best to drive both and it would probably be best to synchronize their movement.

The normal empty bucket side of the cableway could be used to carry plums from the dam excavations in the opposite direc-

tion, provided of course that suitable stone was available.

When ordinary cableways are used for the construction of large dams, in order to obtain the desired capacity, it is necessary to install a number of units usually running approximately parallel to the dam face which work in conjunction with derrick cranes on the surface of the dam. In some cases, the cableways are constructed with cross traversing terminal towers, so that it is possible to feed any point of the dam surface at any period during construction.

With a continuous cableway according to this invention, it would probably be most economical to build the towers at the commencement sufficiently high to complete the dam without adding to their height at periods during the construction of the dam so that work, when once commenced, can be carried on uninterruptedly until completed.

It would also probably be preferable to construct the continuous cableway so that the trestles would be in a line with the finished crest of the dam and build them into the dam.

With regard to the power required, the following details are presented as indicating what the applicant believes to be suitable figures, but they are not to be taken as limitative in any way of the scope of the invention. A 360 ton per hour capacity continuous cableway 6000 ft. long, as described herein, carrying net loads of 6 tons in one direction only for the full length of the dam and traversing at a speed of 100 yds. per min. would, it is believed, require only 27 to 30 B. H. P. to drive it, and such power, it is believed, would suffice to overcome all friction losses and also the motor and gearing losses when normally transporting concrete or medium sized plums.

The carrier rail rope pulleys it is assumed in the above would be fitted with ball bearings. It would, however, be advisable to install a larger motor to overcome the effects of buckets rising to and receding from the trestles, in the event of the correct spacing of buckets not being strictly adhered to. A 75 B. H. P. motor would give a hoisting speed of 100 yds. per min.

The above figures show a considerable saving in power compared with the usual type of cableway. According to certain current practice, each unit cableway of 90 tons hourly capacity 2000 ft. long only of previously known type would require a motor of 120 B. H. P.

Except in cases of small dams a continuous cableway as described herein would, it is believed, prove more economical than a number of ordinary cableway units capable of giving a combined equal hourly capacity. The advantages of the continuous cableway increases considerably when the length of the dam exceeds 2000 ft. especially so when the

material can be loaded at an end terminal station above the dam.

It will of course be understood that the invention is not restricted to the plant or the method of operation hereinbefore described. The plant has been described only in sufficient detail to enable those skilled in the art to arrange the details. For example, any convenient structural or mechanical details may be introduced to enable a cableway to work properly, such as the proper supporting of cables, guying of standards, anchorages, tensioning of cables or ropes, etc.

Under certain conditions it might be possible to work the cableway with very little power indeed. For example, by utilizing the weight of loaded buckets moving from an elevated loading station and causing the rope 3 to move at a suitable speed under brake control.

It will of course be realized that certain terms used in the description and claims are not to be interpreted in a limitative sense.

For example when the word "bucket" is used it is intended to include any kind of bucket, skip or cage, and may also include, if the context will allow, any load supported in slings or otherwise. The word "carriage" may mean any carrier, trolley or wheeled frame traversable along or on the standing rope.

Having now particularly described and ascertained the nature of my said invention and in what manner the same is to be performed, I declare that what I claim is:

1. A cableway system having in combination, a continuous rail, a transmission rope traveling contiguous to said rail, a load carrying means, a carriage adapted to travel upon said rail for supporting said load carrying means, means for transferring said load carrying means with its load from said rail to said rope and means for giving slack to the rope for permitting the bucket to descend from said carriage.

2. A cableway system having in combination a standing cable, a transmission rope having a predetermined amount of slack, a bucket, a carriage for supporting said bucket from said cable, manually operated means for transferring the weight of said bucket from said carriage to said rope and the slack of the latter allowing the bucket to gravitate to its unloading position.

3. A cableway system having in combination, standing cable, a transmission rope having a predetermined amount of slack, a plurality of buckets, a carriage for supporting each bucket from said standing cable, manually operated means for transferring the weight of said buckets equivalent and their loads from said carriages to said rope and the slack of the latter allowing the bucket having its weight and load transferred to said rope to gravitate to an un-

loading position, and thus to permit of the raising of a bucket previously unloaded by taking up the slack in said rope in which the latter is supported, and means for controlling the gravitational action of the loaded bucket.

4. In combination with a pair of supporting ropes, a carriage, manually operated means for supporting said carriage for travel on said ropes, a bucket and manually operated means for solely supporting the bucket on one of the ropes to pick up the slack in the same and thereby descend to unloading position.

15 5. In combination, a rail or standing cable, a transmission rope, a carriage supported from the rail, a bucket, adjustable means for supporting the bucket from the carriage or from said rope and means for clamping the carriage to the rope.

20 6. A conveyor structure for a cableway comprising a wheel supported carriage, a load supporting device, a hanger adapted to be connected to said load supporting device, and means for raising and lowering the hanger relative to said carriage, consisting of a block and tackle mechanism directly connected to the hanger and supported by said carriage.

25 30 7. In combination, a rail or standing cable,

a transmission rope, a carriage supported on said cable for travel, means for clamping the carriage to the transmission rope to be moved thereby, a load supporting structure including a hanger adjustable relative to the carriage, and a block and tackle mechanism carried by the carriage and engaging the hanger whereby the latter may be raised and lowered into operative engagement with said rope.

35 8. In combination, a stationary cable, a transmission rope, a carriage supported on said cable and including a pair of pulleys in operative engagement with the said rope, a brake device for one of said pulleys, a load supporting device, a hanger carrying said load supporting device and movably associated with said carriage, a pulley carried by said hanger, a block and tackle mechanism carried by the carriage and connected to the hanger for raising and lowering the same and thereby adapted to place said hanger pulley into engagement with said rope to support the weight of said load supporting device solely from said rope and means for 40 45 50 55 clamping the carriage to said rope to receive movement therefrom.

In testimony whereof I hereto affix my signature this 17th day of April, 1926.

CHARLES FISHER.
